UNITED STATES PATENT OFFICE.

DANIEL A. DALY, OF NEW YORK, N. Y., ASSIGNOR TO UNITED STATES METAL PRODUCTS CO., OF NEW YORK, N. Y., A CORPORATION OF MASSACHUSETTS.

STAIR CONSTRUCTION.

1,101,012.

Specification of Letters Patent. Patented June 23, 1914.

Application filed March 5, 1913. Serial No. 752,248.

To all whom it may concern:

Be it known that I, DANIEL A. DALY, a citizen of the United States, and a resident of the borough of Brooklyn, city of New York, county of Kings, and State of New York, have invented certain new and useful Improvements in Stair Construction, of which the following is a specification.

This invention relates to improvements in stair construction.

By the use of my invention I produce an exceedingly simple and inexpensive construction whereby an effective non-slipping tread is provided which is an integral part 15 of the structure and a sanitary cove is formed between a tread of suitable filling material and a metallic riser.

Referring now to the accompanying drawings, in which similar reference 20 characters designate corresponding parts throughout the several views, Figure 1 is a side elevation of a section of a stair embodying my invention; and Fig. 2 is a plan view of a stair tread embodying my invention.

In the preferred embodiment of my invention I provide a series of sections each 25 formed of a single sheet of metal, each section comprising a supporting tread, a riser having an outwardly bent portion contiguous to the supporting tread and adapted to 30 provide a sanitary cove between the riser and a suitable filling material, and a level indicator for such material, a nosing, a non-slipping tread portion composed of corrugated metal having staggered ridges formed 35 by cutting suitable apertures in said metal, said tread portion projecting inwardly from the nosing, spaced from the supporting tread of the preceding section and having a bearing flange 40 contacting therewith and a suitable filling material filling the space between the non-slipping tread portion and the supporting tread.

Referring now to these drawings 1 designates a section of stair construction formed 45 of a single sheet of metal and comprising a supporting tread 2 which may have a flange at the lateral end thereof, riser 3, nosing 4, and a metallic non-slipping tread portion 5 projecting inwardly from the nosing and overhanging the supporting tread of the preceding section, suitably spaced therefrom and having a bearing contact therewith by means of a flange 6. As shown, the supporting tread of one section bears upon a

horizontal web portion 7 formed between the riser 3 and nosing 4 of the succeeding section.

The overhanging non-slipping tread portion 5 is preferably formed of corrugated metal, the ridges 8 of which are staggered in relation to each other by having portions of alternate ridges cut away as at 8^a, and these staggered ridges form, when so embedded in a suitable filling material 9 that the tops 60 of such ridges will be flush with such material, a very efficient non-slipping tread. This filling material may be cement, lead, carborundum, or other suitable tread material.

The riser 3, as illustrated, is provided contiguous to the supporting tread with an outwardly bent portion 10 which forms with the filling material 9 a sanitary cove 11 between such riser and the filling material 9, 75 thus preventing the collection of dust, etc., at this point, and the apex of such outwardly extending cove-forming portion provides an indicator to permit the workmen to bring the filling material to the proper level. 80

It will be obvious that when the space between the supporting tread, metallic non-slipping tread portion and cove-portion is filled with cement, lead, carborundum, or other suitable material, an extremely inexpensive non-slipping tread construction will be provided, which non-slipping tread will be an integral portion of the stair construction, and, furthermore, the forming from a single sheet of metal stair sections embodying a supporting-tread, riser, nosing and non-slipping tread portion, will greatly reduce the cost of manufacture of the construction. 85 90

Having described my invention, I claim: 95

1. In stair construction, a section formed of a single sheet of metal, comprising a supporting tread, a riser, a nosing and a non-slipping tread portion projecting inwardly from the nosing. 100

2. In stair construction, a section formed of a single sheet of metal comprising a supporting tread, a riser, a nosing and a non-slipping tread portion projecting inwardly from the nosing and formed of corrugated metal having staggered ridges. 105

3. In stair construction, a metallic supporting tread formed on one section, a nosing and a metallic non-slipping tread portion integrally formed on another section, 110

the non-slipping tread portion being spaced from the said supporting tread and provided with apertures, and a suitable filling material filling the space between the supporting tread and non-slipping tread portion and embedding the major portion of the latter.

4. In stair construction, a section formed of a single sheet of metal comprising a supporting tread, a flange along the lateral edge of said tread, a riser, a nosing, and a non-slipping tread portion projecting inwardly from the nosing and formed of corrugated metal having staggered ridges.

5. In stair construction, a section formed

of a single sheet of metal comprising a supporting tread, a flange along the lateral edge of said tread, a riser, a nosing, and a non-slipping tread portion projecting inwardly from the nosing and formed of corrugated metal having staggered ridges.

In witness whereof, I have signed my name to the foregoing specification in the presence of two subscribing witnesses.

DANIEL A. DALY.
